J. C. McMEEKEN

WASHBOILER PROTECTOR

Filed Sept. 22, 1925

By

Lacy & Lacy, Attorneys

UNITED STATES PATENT OFFICE.

JOHN C. McMEEKEN, OF EWEN, MICHIGAN.

WASHBOILER PROTECTOR.

Application filed September 22, 1925. Serial No. 57,887.

To all whom it may concern:

Be it known that I, JOHN C. McMEEKEN, a citizen of the United States, residing at Ewen, in the county of Ontonagon and State of Michigan, have invented certain new and useful Improvements in Washboiler Protectors, of which the following is a specification.

This invention relates to a protector adapted for use upon a wash boiler so that when the wash boiler is filled with water and clothes and is lifted from one place to another there will be no danger of the bottom of the wash boiler being dented when set down. It often happens that when a wash boiler which is filled with water and clothes is set down upon a cement floor or upon the top of a stove it will receive a blow which will so dent it that a hole will be formed in the boiler or the seam which connects the bottom of the boiler with the walls will spring loose and the boiler thereby caused to leak and be rendered useless.

One object of the invention is to provide a guard which can be readily applied to a wash boiler of a conventional construction and securely held in place by suspending means engaged with the handles of the boiler.

Another object of the invention is to so connect the suspending means with the band which fits upon the lower portion of the boiler that the suspending means will not interfere with ready application of the band to the boiler.

Another object of the invention is to so construct the suspending means that they may be easily engaged with the handles of the boiler and adjusted longitudinally so that the protector may be applied to boilers of varying depths and firmly held in place.

While it is stated that the protector is for use in connection with wash boilers, it will be understood that it could also be used in connection with the other receptacles which are intended to receive heavy loads and moved from one place to another while loaded.

This invention is illustrated in the accompanying drawing, wherein

Figure 1 is a view in elevation showing a wash boiler of a conventional construction and the improved protector applied thereto;

Fig. 2 is a perspective view of the protector, and

Fig. 3 is a fragmentary sectional view taken on the line 3—3 of Fig. 1.

The wash boiler which is indicated in general by the numeral 1 and closed at its upper end by a cover 2 is of a conventional construction. Wash boilers are, as a general rule, of greater length than width and are provided with rounded end portions. Therefore, the protector, as illustrated in connection with a wash boiler, has its boiler-engaging band 3 formed as shown in Fig. 2 so that it will conform to the contour of the wash boiler to which it is to be applied. The band 3 is formed of angle metal and includes a lower horizontal flange 4 which fits beneath the boiler and engages the bottom thereof, as shown in Fig. 3, and a vertically extending side flange 5 which extends upwardly from the outer side edge of the lower flange 4 and engages the outer face of the walls of the boiler. The band 3 will, of course, be formed the proper length and width to snugly fit upon a boiler of a size with which it is to be used. A bar or strip 3' extends longitudinally of the protector to brace the protector and assist in shielding the bottom of the boiler.

In order to retain the band in place upon the boiler, there has been provided suspending means of a special construction so that the band may be suspended from the handles of the wash boiler. A handle is provided at each end of the boiler and each handle is formed with a hand grip 6 secured at its ends to the arms or brackets 7 which extend from the hand grip to the wall of the boiler and are provided at their inner ends with base portions 8 soldered or otherwise secured to the boiler. The suspending means are of a duplicate construction and each includes a yoke 9 formed from a strand of rod metal bent intermediate its length to provide arms 10 which extend downwardly in diverging relation and have their lower ends passed through openings 11 formed in the vertical flange of the band 3. Heads 12 are formed at the ends of the arms 10, as shown in Fig. 3, to hold the arms in the openings 11, the heads being countersunk so that they will not extend from the inner face of the flange 5 and prevent the band

from being readily fitted upon the boiler. A rod 13 which is in the form of an elongated eye bolt has its lower end portion formed into an eye 14 which fits upon the 5 yoke 9 at the connected upper ends of the arm 10. The threaded upper end portion of the rod 13 slidably passes through an opening formed in the bridge 15 of the handle engaging grapple 16 and carries a nut 17 which 10 engages the upper face of the bridge 15 and when rotated in one direction will serve to draw the rod 13 upwardly so that the band 3 will be drawn into tight engagement with the boiler and firmly held in place. The 15 arms 18 of the grapple extend upwardly from the yoke and have their upper free end portions formed into hooks 19 adapted to engage the upper edges of the arms 7 of the handle. In the present illustration, the 20 grapples have been shown so proportioned that the arms 18 may be passed through the handles between the arms 7 and then moved downwardly so that the hooks 19 will engage the upper edges of the bracket arms. 25 It should be further noted that the grapples will preferably be formed of metal having resiliency sufficient to permit the arms 18 to have movement towards and away from each other. The arms of the grapples can, 30 therefore, be moved towards each other as the grapples are forced downwardly through the handles of the boiler and their hooked ends readily engage the arms of the handles. There has, therefore, been provided a boiler 35 guard which is of a simple construction and which may be easily applied and firmly held in place.

Having thus described the invention, I claim:

40 1. The combination with a receptacle including a bottom, walls extending upwardly from said bottom, and handles carried by said walls and each including side arms secured at their inner ends to the walls, of a 45 guard for said receptacle comprising a band fitted about the lower end thereof and having a horizontal flange engaging the bottom of the receptacle and a vertical flange engaging the outer faces of said walls, and 50 means suspending said band from said handles.

2. The combination with a receptacle including a bottom, walls extending upwardly from said bottom, and handles carried by 55 said walls and each including side arms secured at their inner ends to the walls, of a guard for said receptacle comprising a band fitted about the lower end thereof and having a horizontal flange engaging the bottom 60 of the receptacle and a vertical flange engaging the outer faces of said walls, means suspending said band from said handles, said suspending means each comprising a yoke secured to the vertical flange of said 65 band and extending upwardly therefrom; a

grapple engaged with the side arms of a handle and extending downwardly therefrom, and a rod carried by said yoke and extending upwardly therefrom and adjustably engaged with said grapple whereby 70 said band may be drawn into firm engagement with said receptacle.

3. The combination with a receptacle including a bottom, walls extending upwardly from said bottom, and handles carried by 75 said walls and each including side arms secured at their inner ends to the walls, of a guard for said receptacle comprising a band fitted about the lower end thereof and having a horizontal flange engaging the bottom 80 of the receptacle and a vertical flange engaging the outer faces of said walls, means suspending said band from said handles, said suspending means each comprising a yoke secured to the vertical flange of said 85 band and extending upwardly therefrom, a grapple engaged with the side arms of a handle and extending downwardly therefrom, and means connecting said yoke and grapple, said connecting means being adjustable longitudinally to draw said band 90 into firm engagement with said receptacle.

4. A receptacle guard comprising a band adapted to fit about the bottom of a receptacle and having a horizontal flange to 95 fit beneath the receptacle and a vertical flange to extend along the outer faces of the walls of the receptacle, grapples adapted for engagement with handles of the receptacle, and suspending means connected with said band and extending upwardly and adjustably connected with said grapples whereby said band may be drawn into firm engagement with the receptacle.

5. A receptacle guard comprising a band 105 adapted to fit about the bottom of a receptacle and having a horizontal flange to fit beneath the receptacle and a vertical flange to extend along the outer faces of the walls of the receptacle, yokes carried 110 by the vertical flange and extending upwardly therefrom, grapples adapted for engagement with handles of the receptacle, and rods carried by said yokes and connected with said grapples for longitudinal 115 adjustment whereby said band may be drawn into firm engagement with the receptacle.

6. A receptacle guard comprising a band 120 adapted to fit about the bottom of a receptacle and having a horizontal flange to fit beneath the receptacle and a vertical flange to extend along the outer faces of the walls of the receptacle, yokes carried 125 by the vertical flange and including arms extending upwardly in converging relation and connected at their upper ends, grapples adapted for engagement with handles of the receptacle, and rods having their lower ends engaged with said yokes at the connected 130

upper ends of their arms, said rods having their upper end portions adjustably engaged with said grapples and adapted to draw the band into firm engagement with the receptacle.

7. A receptacle guard comprising a band adapted to fit about the bottom of a receptacle and having a horizontal flange to fit beneath the receptacle and a vertical flange to extend along the outer faces of the walls of the receptacle, yokes carried by the vertical flange and including arms extending upwardly in converging relation and connected at their upper ends, grapples each including a crosshead provided with an opening and arms extending upwardly from

the crosshead and formed with hooks at their upper ends for engagement with handles of the receptacle, and rods having their lower ends formed into eyes engaged with said yokes at the connected upper ends of their arms, said rods having threaded upper end portions extending through the openings in the bridges of said grapples, and nuts threaded upon said rods and engaging the bridges of said grapples whereby said rods may be moved longitudinally and said band drawn into firm engagement with the receptacle. 20 25

In testimony whereof I affix my signature.

JOHN C. McMEEKEN. [I. s.]
